(57) **CLAIM**

The ornamental design for a power strip surge-protected adaptor, as shown and described.

DESCRIPTION

FIG. 1 is a top plan view of a power strip surge-protected adaptor, showing a first embodiment of my new design; FIG. 2 is a front elevational view thereof, the back elevational view being a mirror image thereof; FIG. 3 is a right-side elevational view thereof; FIG. 4 is a left-side elevation view thereof; FIG. 5 is a bottom plan view thereof; FIG. 6 is a top plan view of a power strip surge-protected adaptor, showing a second embodiment of my new design; FIG. 7 is a front elevational view thereof, the back elevational view being a mirror image thereof; FIG. 8 is a right-side elevational view thereof; FIG. 9 is a left-side elevation view thereof; and, FIG. 10 is a bottom plan view thereof. The electrical slots, power cord, and indicator light shown in broken lines in FIGS. 1-5 are illustrated environmental matter, and form no part of the claimed design. The electrical slots, power cord, indicator light, and jacks shown in broken lines in FIGS. 6-10 are illustrated environmental matter, and form no part of the claimed design.
